BOTTLE OPENER OR THE LIKE

Robert P. Dietz, Cincinnati, Ohio, assignor to Dieman,
Inc., Cincinnati, Ohio, a corporation of Ohio

Filed Apr. 21, 1958, Ser. No. 50,554

Term of patent 14 years

(Cl. D44—29)

Fig. 2

Fig. 3

Fig. 1 is a side elevational view of a bottle opener or the like, showing my new design.

Fig. 2 is a bottom plan view thereof.

Fig. 3 is a top plan view thereof.

I claim:

The ornamental design for a bottle opener or the like, as shown.
